R. H. DIXON

CENTRIFUGAL PUMP

Original Filed Dec. 12, 1919

Ralph H. Dixon, INVENTOR:
BY
Graentzel and Richards ATTORNEYS.

UNITED STATES PATENT OFFICE.

RALPH HILLIARD DIXON, OF NEWARK, NEW JERSEY.

CENTRIFUGAL PUMP.

Application filed December 12, 1919, Serial No. 344,300. Renewed September 3, 1921. Serial No. 498,571.

To all whom it may concern:

Be it known that I, RALPH H. DIXON, a citizen of the United States, residing at Newark, in the county of Essex and State 5 of New Jersey, have invented certain new and useful Improvements in Centrifugal Pumps; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15 This invention has reference, generally, to improvements in pumping devices, such as centrifugal pumps; and, the present invention relates, more particularly, to a novel centrifugal pump construction of the single 20 or multiple-stage type, in which the enclosing housing or casing is primarily in the form of a single hollow cylindrical casting, thus dispensing with the costly construction of splitting the main cylinder or casing 25 horizontally, the arrangement of the impeller-shaft and the impeller being such that these elements can be slipped into an open-ended portion of the cylinder and operatively mounted within the cylinder, the 30 open-ended portion of the cylinder being closed by a member, hereinafter termed the suction-head.

The present invention, therefore, has for its principal object to provide a centrifugal 35 pump comprising a hollow cylindrical casing cast in a single piece, with an impeller-shaft and impeller thereon, and a suction-head secured to an open-ended portion of the cylinder, all in a manner hereinafter 40 more particularly set forth.

The invention has for its further object to provide a novel arrangement and construction of impellers, all mounted upon an impeller-shaft, within a cylindrical casing, 45 and cooperating therewith in a manner hereinafter stated, whereby the novel results of the hereinafter described multi-stage type of centrifugal pump are obtained. Other objects of the present invention not at this time more particularly 50 enumerated will be clearly understood from the following detailed description of the said invention.

With the various objects in view, the said 55 invention consists, primarily, in the novel

centrifugal pump hereinafter set forth; and, the said invention consists, furthermore, in the novel arrangements and combinations of the several devices and parts, as well as in the details of the construction of the said parts, all of which will be more fully described in the following specification, and then finally embodied in the clauses of the claims which are appended to and which form an essential part of the 65 said specification.

The invention is illustrated in the accompanying drawings, in which:—

Figure 1 is a longitudinal vertical sectional representation of a centrifugal pump 70 made according to and embodying the principles of the invention, said view illustrating one embodiment of the various elements of the apparatus; and Figure 2 is an elevation of one of the impellers, looking in the direction of the arrow X in said Figure 1, and with the impeller-shaft and a spacer thereon represented in cross-section, said section being taken on line 2—2 in said Figure 1.

Similar characters of reference are employed in said above described views, to indicate corresponding parts.

Referring now more particularly to Figure 1 of the drawings, the reference-character 1 indicates one form of multi-stage centrifugal pump embodying the principles of the present invention, the same comprising a main housing or cylindrical casing 2, which is closed at its one end, as at 4, the 90 said closed end being formed with a bearing-member 3. The opposite end of the said housing or casing is open, as at 5, said open-ended portion being closed by means of a suitably formed suction-head or plate, as 6, 95 suitably secured upon the said end-portion of the housing or casing 2 by means of screw-studs or tap-bolts 7, or other suitable fastening means.

That portion of the housing or casing 2, 100 indicated by the reference-character 8 may be provided with flanges 9, indicated in dotted outline in said Figure 1, said flanges being provided with suitably disposed perforations for the reception of bolts by means 105 of which the said housing or shell is secured to a base 10, substantially in the manner as shown. At the inner end of the cylindrical chamber 11, contiguous to the closed end 4 of the casing 2, is an annular 110

raceway, as 12, which is provided with an outlet or discharge-member, as 13, preferably internally screw-threaded, as at 14, for the reception and attachment thereto of a discharge-pipe, as will be clearly evident. Within the previously mentioned bearing-member 3 may be arranged a pair of journal-brasses 15 and 16, or the like, and a suitable packing 17, the same being suitably disposed about the portion 19 of an impeller-shaft 18 and secured in place by means of a gland or screw-cap 19, suitably screwed upon the screw-threaded portion 20 of the bearing-member 3, as shown. Lubrication may be provided by means of a grease-cup 21, suitably connected with the feed-ducts 22 and 23, as shown in said Figure 1.

The previously-mentioned suction-head is provided upon its inner face with a member 24 which is snugly fitted in the open end 5 of the housings or casing 2, the said member 24 being provided with a tubular hub 25 in which is fitted a bearing-ring 26. The cone-shaped tubular portion 27 of said member 24 connects with a corresponding cone-shaped tubular portion 28 with which the suction-head 6 is provided, the said cone-shaped tubular portion 28 leading from the internally screw-threaded opening or inlet 29 with which the said suction-head or plate 6 is provided, substantially as shown in said Figure 1 of the drawings.

Suitably keyed, or otherwise secured, upon that portion of the impeller-shaft which extends longitudinally through the cylindrical chamber 11 are a series of impellers 30, 31 and 32, the said impellers being also positioned against movement longitudinally upon said shaft by the off-set 33, the spacing sleeves 34, and the nut 35 screwed upon the screw-threaded end-portion 36 of said shaft.

As shown, the impeller 30 consists of a pair of parallel discs 37 and 38, the disc 38 being of smaller diameter than the disc 37, the two discs being connected by means of suitably disposed impeller-blades or vanes 39, and intermediately disposed deflector blades 40, arranged substantially as shown in Figure 2 of the drawings, the said discs and vanes being integrally cast, and the united elements providing an impeller having both a direct peripheral discharge, as well as a side-discharge on one side at the outer circumferential edge-portion of the smaller disc 38. To mount this impeller 30 upon the shaft 18, the said disc 38 has an inwardly extending mounting hub 41, which also serves as a deflector for directing the flow of the liquid in a direction between the two discs 37 and 38 and against the impeller-blades, so as to be discharged laterally at the periphery of the impeller, as will be clearly evident. The other disc 37 is also

formed with a tubular hub, as 42, a portion of which is rotatably disposed in the bearing-ring 26 heretofore mentioned, the intake-throat 43 of said hub 42, being in communication with the alined tubular portions 27 and 28, for conveying the impelling fluid into and between the two discs 37 and 38 of the impeller 30.

Similarly, the impeller 31 consists of a pair of parallel discs 43 and 44, the disc 44 being of smaller diameter than the disc 43, the two discs being also connected by means of suitably disposed impeller blades or vanes 45 and intermediate deflector-blades 46, similar to those illustrated in said Figure 2 of the drawings, the said discs and vanes being integrally cast, and the united elements providing an impeller also having a direct peripheral discharge, as well as a side-discharge on one side at the outer circumferential edge-portion of the smaller disc 44. To mount this impeller 31 upon the shaft 18, the said disc 44 is likewise provided with an inwardly extending mounting hub 47, which also serves as a deflector for directing the flow of the impelling fluid in a direction between the two discs 43 and 44 and against the impeller-blades, so as to be discharged laterally at the periphery of this impeller, as will be evident. As shown, the other disc 43 has an intake-opening 48 for conveying the impelling fluid into and between the two discs 43 and 44 of the impeller 31. Coming now to the third impeller 32 which is concentrically disposed with relation to the annular raceway 12, this impeller 32 consists of a pair of parallel discs 49 and 50, both of the same size, these two discs being connected by means of suitably disposed impeller-blades or vanes 51 and intermediate deflector blades 52, similar to those illustrated in said Figure 2 of the drawings, the said discs and vanes being integrally cast, and the united elements being arranged, so that the impeller in this instance has only a direct peripheral discharge into the annular raceway 12. To mount this impeller 32 upon the shaft 18, the said disc 50 is likewise provided with an inwardly extending mounting hub 53, which also serves as a deflector for directing the flow of the impelling fluid in a direction between the two discs 49 and 50 and against the impeller-blades, so as to be discharged peripherally from said impeller 32 directly into the raceway 12. As shown, the other disc 49 has an intake opening 54 for conveying the impelling fluid into and between the two discs 49 and 50 of the said impeller 32.

Having in the foregoing description set forth the general construction and an arrangement and combination of the several devices and parts, comprising a multi-stage centrifugal pump embodying the principles

of the present invention, I will now briefly set forth its operation.

As will be evident from an inspection of said Figure 1 of the drawings, the impelling fluid enters the pump-casing at its inlet-opening 29 and passes through the cone-shaped openings or ducts 28 and 27 into the intake throat 43 of the first impeller 30. The fluid passes at the central open portion of the said impeller into the space between the two discs 37 and 38, being directed by the concave surfaces of the deflector-blades 40 directly upon the concave surfaces of the impeller-vanes or blades 39, so as to exert its impelling force upon said vanes or blades 39, as will be understood. The fluid is discharged at the peripheral opening of the said impeller 30, against the inner wall of the cylinder 2, and the impeller being also formed with the lateral circumferential side-opening 55, the fluid first forms a substantially solidly moving fluid-wall, against which the inrushing and impelling fluid makes its own elbows into the space between the two discs 38 and 43 of the impellers 30 and 31. The fluid is thereupon picked up by the second impeller 31, by passing into the central intake-opening 48 of said impeller 31 and into the space between the two discs 43 and 44, being also directed by the concave surfaces of the deflector-blades 46 directly upon the concave surfaces of the impeller-vanes or blades 45, so as to exert its impelling force upon said vanes or blades 45, similar as in the first-mentioned impeller 30. The fluid is likewise discharged at the peripheral opening of the said impeller 31, against the inner wall of the cylinder 2, and this impeller being also formed with a lateral circumferential side-opening 56, the fluid here also forms a substantially solidly moving fluid-wall, against which the inrushing and impelling fluid again makes its own elbows into the space between the two discs 44 and 49 of the impellers 31 and 32. The fluid is thereupon picked up by the third impeller 32, by passing into the central intake-opening 54 of said impeller 32 and into the space between the two discs 49 and 50, being also directed by the concave surfaces of the deflector-blades 52 directly upon the concave surfaces of the impeller-vanes or blades 51, as in the heretofore-mentioned impellers 30 and 31, and the fluid being finally discharged radially from the peripheral opening of said impeller 32 into the annular race-way 12, passing with accelerated force from the discharge-member or element 13 of the pump-casing or cylinder 2, as will be clearly evident.

While in the form of multi-stage centrifugal pump herein-above described and illustrated in said Figure 1 of the drawings, I have shown an arrangement of but three impellers, it will be clearly understood that

this arrangement of impellers may be departed from, and the number of impellers may be decreased or increased, if so desired.

It will also be evident, that the herein-described construction of centrifugal pump, whether of the single or multiple type, allows the manufacture of such pumps without the costly arrangement of splitting the casing horizontally, the assembled impellers and shaft being slipped into the cylinder 2, through its open end, before securing the suction-head 6 in its position over the open end of said cylinder.

Furthermore, by the present arrangement of the several impellers upon a single shaft, one impeller feeds the other, and so on according to the number of impellers employed, thereby overcoming the possibility of the column of fluid to lag in the suction-pipe, and finally stop the operation of the pump.

Of course I am aware, that some changes may be made in the general arrangements and combinations of the various devices and parts, as well as in the details of the construction of the said parts, without departing from the scope of the present invention as set forth in the foregoing specification and as defined in the clauses of the claims which are appended thereto. Hence, I do not limit my present invention to the exact arrangements and combinations of the various devices and parts as described in the said specification, nor do I confine myself to the exact details of the construction of the said parts, as illustrated in the accompanying drawings.

I claim:

1. A centrifugal pump comprising a cylindrical casing, an impeller-shaft within said casing, and a plurality of impellers mounted upon said shaft, each impeller being provided with a centrally disposed inlet-opening, and all of the impellers except the last one upon said shaft being provided at their peripheries with openings for combined direct and lateral discharge of the impelled fluid, said last-placed impeller having merely a direct peripheral discharge opening.

2. A centrifugal pump comprising a one-piece cylindrical casing, said casing having one end closed and the other end open, a bearing-member connected with and extending from the wall providing said closed end, said casing being provided near said wall with an annular raceway and a discharge-outlet, a plate secured over the open end of said casing, said plate being provided with an inlet-opening in communication with the interior of said casing, an impeller-shaft within said casing and rotatably mounted in the bearing-member thereof, and a plurality of impellers mounted upon said shaft, the impelled fluid being

126

120

136

fed from one impeller into the next succeeding impeller and being finally discharged from the last impeller upon said shaft directly into said raceway.

5. A centrifugal pump comprising a one-piece cylindrical casing, said casing having one end closed and the other end open, a bearing-member connected with and extending from the wall providing said closed end, said casing being provided near said wall with an annular raceway and a discharge-outlet, a plate secured over the open end of said casing, said plate being provided with an inlet-opening in communication with the interior of said casing, an impeller-shaft within said casing and rotatably mounted in the bearing-member thereof, and a plurality of impellers mounted upon said shaft, each impeller being provided with a centrally disposed inlet-opening, and all the impellers except the last one upon said shaft being provided at their peripheries with openings for combined direct and lateral discharge of the impelled fluid, and said last-placed impeller having merely a direct peripheral discharge directly into said raceway.

4. A centrifugal pump comprising a one-piece cylindrical casing, said casing having one end closed and the other end open, a bearing-member connected with and extending from the wall providing said closed end, said casing being provided near said wall with an annular raceway and a discharge-outlet, a plate secured over the open end of said casing, said plate being provided with an inlet-opening in communication with the interior of said casing, an impeller-shaft within said casing and rotatably mounted in the bearing-member thereof, and a plurality of impellers mounted upon said shaft, all of said impellers except the last one upon said shaft comprising a

pair of discs connected by intermediately disposed impeller and deflector vanes, each pair of discs being of different diameters so as to provide each one of said impellers at its periphery with a discharge opening for discharging the impelled fluid laterally from the impeller, the larger disc of each impeller being provided with a centrally disposed inlet, said last-placed impeller comprising a pair of discs of the same size connected by intermediately disposed impeller and deflector vanes, said last-mentioned impeller having a direct peripheral discharge into said raceway, and one of its discs being provided with a centrally disposed inlet opening.

5. An impeller for a centrifugal pump comprising a pair of discs of different size, impeller and deflector vanes between said discs, said discs providing the impeller at its periphery with a discharge-opening for combined direct peripheral and lateral side discharge of the impelled fluid from the impeller.

6. An impeller for a centrifugal pump comprising a pair of discs of different size, impeller and deflector vanes between said discs, said discs providing the impeller at its periphery with a discharge-opening for combined direct peripheral and lateral side discharge of the impelled fluid from the impeller, the larger one of said discs being provided with a centrally disposed inlet-opening, and the smaller disc having an inwardly extending tubular hub for mounting the impeller upon a shaft.

In testimony that I claim the invention set forth above I have hereunto set my hand this 10th day of December, 1919.

RALPH HILLIARD DIXON.
